UNITED STATES PATENT OFFICE.

TALBOT C. DEXTER, OF PEARL RIVER, NEW YORK, ASSIGNOR TO THE DEXTER FOLDER COMPANY, OF NEW YORK, N. Y.

PAPER-REGISTERING INSTRUMENT.

SPECIFICATION forming part of Letters Patent No. 650,709, dated May 29, 1900.

Application filed October 9, 1899. Serial No. 732,987. (No model.)

To all whom it may concern:

Be it known that I, TALBOT C. DEXTER, a citizen of the United States, and a resident of Pearl River, in the county of Rockland, in the State of New York, have invented new and useful Improvements in Paper-Registering Instruments, of which the following, taken in connection with the accompanying drawings, is a full, clear, and exact description.

10 The objects of my present invention are primarily to provide a simple and efficient instrument that shall be capable of registering the paper both longitudinally and laterally, and, secondarily, to adapt said instrument to be used on a paper-folding machine in which the paper-delivering tapes are disposed parallel with the folding-rolls; and to that end the invention consists in the novel construction, combination, and arrangement of the mechanism for operating the paper-registering instrument and auxiliary devices connected therewith, as hereinafter described, and set forth in the claims.

In the accompanying drawings, Figure 1 is a side elevation of a paper-folding machine equipped with my improved paper-registering devices. Fig. 2 is a plan view of the same. Fig. 3 is an enlarged vertical transverse section on line Y Y in Fig. 2, showing the registering instrument in position to allow the paper to be delivered under it. Fig. 4 is a further enlarged vertical transverse section of the registering instrument proper in position to register the paper, taken on line X X in Fig. 2. Fig. 5 is a front view of the same. Figs. 6 and 7 are transverse sections on lines V V and Z Z, respectively, in Fig. 5. Fig. 8 is a still further enlarged end elevation of the mechanisms for imparting motion to the registering instrument, and Fig. 9 is a transverse section of the longitudinally-movable bar which carries the registering instrument and means for transmitting motion to said bar.

45 Similar letters and figures of reference indicate corresponding parts.

A represents the main supporting-frame of a paper-folding machine comprising the folding-rolls B B, the blade C, which tucks the paper to be folded into the bite of said rolls, the tapes a a, which deliver the paper into said machine, and the front stop D, which

arrests the advance movement of the paper preparatory to its introduction into the folding-rolls.

55 In the machine here presented the paper-delivering tapes a a are disposed parallel with the folding-rolls B B and receive longitudinal movement from the usual feed-roll E E, from which they travel to suitable rollers a' a' on the opposite side of the machine.

F F are the usual drop-rollers, which are over the feed-roll E, to press the sheet into intimate contact with the feed-roll and cause the same to force the sheet onto the tapes a a, by which the sheet is carried along until arrested by contact with the front stop D.

In the subsequent operation of the blade C introducing the sheet between the folding-rolls B B said sheet is drawn transversely from the tops of the tapes a a. Before this introduction of the paper into the bite of the folding-rolls B B the sheet is required to be registered or adjusted to bring the required line of folding of the sheet in coincidence with the bite of the folding-rolls. To accomplish this in an efficient and accurate manner, I resort to the following construction, combination, and arrangement of parts, to wit:

80 Transversely over the tapes a a is disposed a longitudinally-movable bar G, sliding in suitable guides G' G' on the frame A. By mechanisms hereinafter described said bar receives intermitting reciprocating motion. At 85 opposite sides of the folding-rolls B B, I connect to the bar G brackets composed of shoes b b, receiving said bar through them and having depending from them arms b' b', which carry the registering instruments hereinafter described. Said shoes are adapted to be shifted lengthwise of the bar and are clamped in their required positions by means of set-screws b' b', passing through the shoes and engaging the bar. To permit the shoes to be 90 accurately adjusted in their positions, I mount on the bar G hangers c c, which are likewise adapted to slide lengthwise of the bar and are clamped in position by means of set-screws c'. The lower end of each of said 100 hangers is formed with a nut or screw-threaded sleeve c', through which passes the adjusting-screw c'', which is extended and passes through a nut c'', firmly attached to or inte-

gral with the shoe b , as more clearly shown in Fig. 5 of the drawings. The said adjustment of the bracket-shoe b is effected by loosening the set-screws $b' b'$ and c' , and after the shoe b has been placed approximately in its required position the set-screw c' of the hanger c is tightened, so as to confine said hanger in its position. Then by turning the adjusting-screw c^3 , the shoe b is moved accurately to its required position and is then fastened by tightening the set-screws $b' b'$. The aforesaid adjustment is required to support the registering instrument in the path of the slit or perforation made in the paper for the purpose of registering it thereby. A second adjustment is required of the two bracket-arms $b^2 b^2$ at opposite sides of the folding-rolls to arrest the advance movement of the sheet in such a position as to cause the required line of folding of the sheet in coincidence with the line of the bite of the folding-rolls. This adjustability is obtained by transverse guides d on the under sides of the shoes b and correspondingly-shaped heads d' on the upper ends of the bracket-arms b^2 . Said bracket-arms are thus allowed to be shifted backward or forward parallel with the tapes and support the registering instruments in proper positions to cause them to arrest the forward movement of the sheet precisely in a position to bring the line of folding of the sheet in coincidence with the line of the bite of the folding-rolls. To permit convenient accurate adjustment of the said hanger-arms, I provide the heads d' thereof with screw-threaded sockets e , parallel with the guides d and engaged by the adjusting-screws e' , which pass through rigid lips e^2 on the shoes b and are prevented from moving longitudinally by collars e^3 , attached to the screws in front and rear of the said lips, as shown in Fig. 9 of the drawings. The hanger-arms b^2 are each provided with a vertical guide f , on which is a slide g , to which is pivoted vertically an arm h , preferably by means of a post h' , fastened to or integral with said arm and pivoted at its ends to the heads $g' g'$ of the slide, as more readily seen by reference to Figs. 5, 6, and 7 of the drawings. To the lower or free end of the arm h is fastened the registering point or tongue h^2 , designed to enter into the slit or perforation in the paper to be registered. The slide g receives the requisite intermittent vertical reciprocating motion by mechanism hereinafter described.

In a paper-folding machine having the delivering-tapes $a a$ parallel with the folding-rolls $B B$ it is necessary to sustain the arms $h h$ of the registering instruments yieldingly toward the folding-rolls, so as to allow the paper to be withdrawn laterally out of engagement with the registering-points $h^2 h^2$ without tearing the sheet, and for this purpose the supporting-posts h' of the registering instruments are pivoted, as before described.

By means of stops i , secured to the slide g , and suitable springs i' , holding the arms h in

contact with said stops, the registering instruments are held normally in position to engage the slits or perforations in the sheet 70 passing under said instruments.

To facilitate the entrance of the registering-point h^2 into the slit or perforation in the sheet to be registered, a suitable sheet-depressor, preferably of the form of a suitably-shaped spring-plate j , is attached to a supporting-bracket j' on the slide g to move vertically therewith.

The slide g receives intermittent reciprocating motion from a rock-shaft I , disposed transversely over the tapes $a a$ and mounted in bearings on brackets $II II'$, secured to the frame A . Said rock-shaft has extending from it arms I' , the free ends of which are connected to the slides g by means of pitmen J . Said arms can be shifted lengthwise of the shaft to conform to the position of the brackets, which carry the hereinbefore-described registering instruments. By means of set-screws k , connected to the arms I' and engaging the rock-shaft, said arms are retained in their adjusted positions. The rock-shaft is oscillated by means of a rotary cam K , on which rides a roller l , pivoted to one of the arms of a bell-crank lever L , pivoted to a hanger l' on the frame A . To the other arm of the said bell-crank is connected an upwardly-extending rod L' , which is guided vertically by means of a pin m , projecting from a stationary bracket m' and passing through a vertical slot m^2 in said rod. The upper end of the rod L' is provided with a rigid laterally-projecting bifurcated head L^2 , the two prongs of which have projecting from opposing faces thereof tappets n and n' , bearing, respectively, onto the top and bottom of a tongue o , which projects radially from a collar o' , fastened to the rock-shaft I , as shown more clearly in Fig. 8 of the drawings. The tappet n' , which is subjected to the strain of lifting the slides g , with the registering instrument, by the arms I' , attached to the rock-shaft I , is made adjustable to compensate for the wear of the points of contact of said tappet and tongue o . For this purpose the tappet passes loosely through the prong of the head L^2 and rests with its lower end upon the top of a set-screw o^2 , inserted in a projection o^3 on the rod L' .

One of the chief objects of my present invention is to register the paper laterally by the same instrument which registers said paper longitudinally. For this purpose I employ the longitudinally-movable bar G , hereinbefore described, which bar receives properly-timed intermittent reciprocating motion preferably from the rock-shaft I , which is movable longitudinally and reciprocated by suitable actuating mechanism. To transmit said motion to the bar G , one of the bracket-shoes b has rigidly projecting from it a finger p , which is maintained in engagement with a circumferential groove p' in the attaching-collar of the arm I' , as shown in

Fig. 9 of the drawings. For imparting the required reciprocating motion to the shaft I, I prefer to employ a cam N, fastened to the shaft N', to which the cam K is attached. 5 Upon the cam N rides a roller r, pivoted to the free end of an arm O, which is attached to the shaft q, mounted in bearings q' q', secured to the frame A. A lever O', attached to the shaft q, extends upward therefrom and 10 is connected to the outer end of a rod r', the inner end of which is pivotally connected to a hub projecting from a sleeve r², mounted on the shaft I and held in place by means of collars r³, adjustably secured to the shaft at 15 opposite ends of the sleeve.

To maintain the tappets n and n' in contact with the tongue o during the reciprocating motion of the shaft I, said tongue is elongated or distended in the direction length- 20 wise of the shaft and is preferably provided with grooves or ways for the tappets.

In connection with the described registering instruments I employ the alternately advancing and receding gage or front stop D, 25 similar to that shown in my Letters Patent No. 561,937, dated June 9, 1896. Said front stop rides upon bars 2 2, disposed at right angles to said front stop and supported at their inner ends upon rollers 3 3, pivoted to 30 suitable stationary supports. The outer end of each of said bars has rigidly secured to it a bracket 4, in which is journaled a rod 5, having its inner end screw-threaded and passing through a nut 6, attached to the front 35 stop D. By the turning of the two screw-rods the said front stop is adjusted for different-sized paper to be registered and folded.

To turn the two screw-rods synchronously, I attach to each of them a worm-gear 7, which 40 meshes with a corresponding gear 8, attached to a shaft 9, mounted in arms 10, formed on the brackets 4. A suitable crank or hand wheel 11 is attached to the end of said shaft for turning it. The outer end of each of the 45 bars 2 2 is supported by an arm 12, fixed in a suspended position to a rock-shaft 13 and pivotally connected at its lower end to the bracket 2, as shown more particularly in Fig. 3 of the drawings. The rock-shaft 13 is actuated by a lever 14, fastened thereto and having on its free end rollers 15, engaging a rotary cam 16, which imparts oscillatory motion to said lever.

To facilitate the second advance movement 55 of the paper during the receding of the front stop from its paper-arresting position, I attach to said front stop suitable sheet-depressing devices, preferably of the form of spring-plates s, attached to the free ends of arms t, 60 clamped onto the front stop and extending toward the registering instruments. The tension of the spring-plate may be made adjustable by a set-screw u, connected to the arm t and bearing upon the top of the spring-plate. 65 Said sheet-depressing devices serve to increase the frictional hold of the tapes a a on the overlying sheet.

In the operation of the machine the registering instruments are held in elevated position to allow the incoming sheet to pass under them, and at the same time the front stop D is in its rearmost position to arrest the advance movement of the sheet before the slit- 70 ed portions thereof are carried directly under the registering instruments. Then said 75 instruments descend and the front stop D is drawn forward, which latter causes the sheet to receive a secondary advance movement, and in this movement the registering-points h² enter into the slits in the sheet, and thereby register said sheet longitudinally. 80 As soon as this is effected the longitudinally-movable bar G receives a reciprocating motion, and thereby causes the paper to be shifted laterally and registered in said direction by the entered registering-point h² on the arm h, which is sustained by the stop i. The sheet thus registered is then introduced into the bite of the folding-rolls B B, and in this operation the supporting-arms h of the 90 registering-points h² yield to the draft of the sheet and allows the same to be drawn out of engagement with the registering-points without danger of tearing the sheet.

What I claim as my invention is— 95

1. A combined longitudinally and laterally paper registering instrument provided with means for engaging a slit or perforation in the paper, and actuated to effect said engagement and thereby impart the first register to 100 the paper, and to subsequently move laterally while engaged with the paper, and thereby shift the paper to its second register as set forth.

2. An automatic paper-registering instrument provided with means for engaging a slit or perforation in the paper, means for moving the paper longitudinally under said instrument, mechanism imparting vertical movement to said instrument to effect the aforesaid engagement during the longitudinal movement of the paper, and thereby arrest and register the paper in said direction, and means for moving the engaged instrument laterally, and thereby shifting the paper to 110 its lateral register. 115

3. An automatic paper-registering instrument provided with means for engaging a slit or perforation in the paper, and mounted on a vertically and laterally movable support to 120 register the paper longitudinally and laterally, and connected to said support yieldingly to the withdrawal of the registered paper from said instrument.

4. In a paper-folding machine having the 125 folding-rolls parallel with the paper-delivering tapes, a bracket supported above the plane of the tapes, a vertical guide on said bracket, a slide on said guide, an arm connected to said slide movably at right angles to said 130 tapes, a registering-point on said arm, a stop limiting the movement of said arm in one direction, and mechanisms imparting vertical movement to the aforesaid slide.

5. In a paper-folding machine having the folding-rolls parallel with the paper-delivering tapes, a bracket supported above the plane of said tapes and movable at right angles to the lines of the tapes, a vertical guide on said bracket, a slide on said guide, an arm connected to said slide yieldingly at right angles to the tapes, a registering-point on said arm, a stop limiting the movement of said arm in one direction, mechanism transmitting vertical movement to the slide, and mechanisms imparting the aforesaid movement to the bracket as set forth.

6. In a paper-folding machine having the folding-rolls parallel with the paper-delivering tapes, a bracket supported over the plane of said tapes, a vertical guide on said bracket, a slide on said guide, an arm pivoted to said slide to swing in a horizontal plane, a stop limiting said swinging movement in one direction, a registering-point on the free end of said arm, and mechanism imparting vertical movement to the slide as set forth.

7. In a machine having the folding-rolls parallel with the paper-delivering tapes, a bracket supported over the plane of said tapes movably at right angles to the lines of the tapes, a vertical guide on said bracket, a slide on said guide, an arm pivoted to said slide to swing in a horizontal plane, a stop limiting said swinging movement in one direction, a registering-point on the free end of said arm, mechanism transmitting vertical motion to the slide, and mechanism imparting intermittent reciprocating motion to the aforesaid bracket as set forth.

8. In combination with the paper-conveying tapes, a bracket supported over the plane of said tapes, and provided with a vertical guide, a slide on said guide, a registering instrument connected to said slide and provided with means for engaging a slit or perforation in the paper, a paper-depressing device attached to said slide to move in unison therewith, and mechanism transmitting vertical movement to the slide as set forth.

9. In combination with paper-conveying tapes, a bracket supported over the plane of said tapes and provided with a vertical guide, a slide on said guide, an arm pivoted vertically on said slide, a stop limiting the swinging movement of said arm in one direction, a registering-point carried on the free end of said arm, a sheet-depressing spring attached to the aforesaid slide, and mechanism transmitting vertical movement to the slide as set forth.

10. In combination with the paper-conveying tapes, a longitudinally-movable bar disposed transversely over said tapes, a bracket connected to said bar and provided with a vertical guide, a slide on said guide, an arm connected to said slide, a registering-point on the free end of said arm, a sheet-depressing device carried on the slide, a longitudinally-movable rock-shaft disposed parallel with the aforesaid movable bar, mechanisms imparting

reciprocating and rocking motion to said shaft, means for transmitting reciprocating motion from said rock-shaft to the aforesaid bar, and means for transmitting vertical motion from said shaft to the aforesaid slide as set forth.

11. In combination with the paper-conveying tapes, a longitudinally-movable bar disposed transversely over said tapes, a bracket connected to said bar adjustably lengthwise thereof, a vertical guide on said bracket, a slide on said guide, an arm connected to said slide, a registering-point on the free end of said arm, a rock-shaft parallel with the aforesaid longitudinally-movable bar, means for imparting synchronous reciprocating movement to said shaft and bar, an arm attached to said rock-shaft adjustably lengthwise of the shaft to conform the position of said arm to the position of the aforesaid bracket, and means for transmitting vertical movement from said arm to the aforesaid slide as set forth.

12. In combination with the paper-conveying tapes, a bar disposed transversely over said tapes, a bracket-shoe connected to said bar and provided with a guide disposed at right angles to said bar, a bracket-arm suspended from said guide and adjustably sustained therein, a vertical guide on said arm, a slide on said guide, an arm carried on said slide, a registering-point carried on the free end of the latter arm, and mechanism transmitting vertical reciprocating motion to the slide.

13. In combination with the paper-conveying tapes, a longitudinally-movable bar disposed transversely over said tapes, a bracket fastened to said bar and provided with a vertical guide, a slide on said guide, an arm carried on said slide, a registering-point on the free end of said arm, a longitudinally-movable rock-shaft disposed parallel with the aforesaid bar, mechanisms imparting reciprocating and rocking motion to said shaft, a collar attached to said shaft and provided with a circumferential groove, a finger projecting rigidly from the aforesaid bracket and maintained in engagement with the aforesaid groove to transmit longitudinal movement from the rock-shaft to the aforesaid bar, an arm extending from the aforesaid collar, and a pitman connecting said arm to the aforesaid slide as set forth.

14. In combination with paper-folding rolls and paper-delivering tapes disposed parallel with said rolls, a longitudinally-movable bar disposed transversely over said tapes, brackets connected to said bar at opposite sides of the folding-rolls, and adjustably lengthwise thereof, registering instruments carried on said brackets, a longitudinally-movable rock-shaft disposed parallel with the aforesaid bar, collars attached adjustably to said shaft, and one of said collars provided with a circumferential groove, a finger projecting from one of the aforesaid brackets and held in engage-

ment with said groove, arms extending from the collars and transmitting vertical movement to the aforesaid registering instruments, and mechanisms imparting reciprocating and 5 rocking motion to the aforesaid shaft as set forth.

15. In combination with the paper-folding rolls and paper-delivering tapes disposed parallel with said rolls, a longitudinally-movable 10 bar disposed transversely over said tapes, brackets connected to said bar adjustably lengthwise thereof, and disposed at opposite sides of the folding-rolls, registering instruments carried on said brackets yieldingly toward the folding-rolls and provided with 15 points for engaging slits or perforations in the paper, stops limiting the movements of said instruments in the opposite direction and sustaining the same in position to engage the 20 aforesaid slits or perforations, a longitudinally-movable rock-shaft sustained parallel with the aforesaid bar, mechanisms imparting rocking and reciprocating motion to said shaft, means for transmitting said reciprocating motion to said bar, arms extending from 25 said rock-shaft, and means for transmitting vertical motions from said arms to the aforesaid registering instruments as set forth.

16. In combination with the paper-delivering 30 tapes, a longitudinally-movable bar disposed transversely over said tapes, brackets connected to said bar, registering instruments carried on said brackets and provided with means for engaging slits or perforations in 35 the paper, a longitudinally-movable rock-shaft disposed parallel with the aforesaid bar, mechanism imparting reciprocating motion to the said shaft, means for transmitting said motion to the said bar, a tongue projecting 40 radially from the rock-shaft and distended in a direction parallel with the shaft, a lever provided with contact-points for engaging opposite faces of the aforesaid tongue, and mechanism actuating said lever to transmit rocking 45 motion to the aforesaid shaft by said engagement with the tongue as set forth.

17. In combination with the paper-delivering 50 tapes, a longitudinally-movable bar disposed transversely over said tapes, brackets connected to said bar and provided with vertical guides, slides on said guides, arms pivoted vertically to said slides, registering points on the free ends of said arms for engaging slits in the paper, a longitudinally-movable 55 rock-shaft disposed parallel with the aforesaid bar, a lever imparting reciprocating motion to said rock-shaft, means for transmitting said motion to the aforesaid bar, arms on the rock-shaft imparting vertical movement to the aforesaid slides, a tongue projecting 60 radially from the rock-shaft and distended in a direction parallel with the shaft, a reciprocating rod provided with tappets engaging opposite faces of said tongue, and 65 mechanism actuating said rod to transmit rocking motion to the aforesaid shaft as set forth.

18. In combination with the paper-delivery tapes, alternately advancing and receding front stop, and a registering instrument provided with means for engaging a slit or perforation in the paper, a sheet-depressor connected to the front stop to move therewith and facilitate the secondary advance movement of the sheet as set forth. 70

19. In combination with the paper-delivery tapes, alternately advancing and receding front stop, and a registering instrument provided with means for engaging a slit or perforation in the paper, a sheet-depressing 80 spring connected to the front stop, and means for adjusting the tension of said spring.

20. In combination with the paper-delivering tapes, and alternately advancing and receding front stop, a vertically-movable paper-registering instrument provided with means for engaging a slit or perforation in the paper, a sheet-depressor moving vertically with said instrument to facilitate the aforesaid engagement, and a sheet-depressor connected to the 85 front stop to move therewith and facilitate the secondary advance movement of the sheet. 90

21. In combination with the paper-delivering tapes, and alternately advancing and receding front stop, a bracket sustained over 95 said tapes, a vertical guide on said bracket, a slide on said guide, an arm on said slide provided on its free end with means for engaging a slit or perforation in the paper, a sheet-depressing spring connected to said 100 slide, mechanism transmitting reciprocating motion to the slide, and a sheet-depressing spring connected to the front stop to move therewith as set forth.

22. In combination with paper-folding rolls 105 and paper-delivering tapes disposed parallel with said rolls, an alternately advancing and receding front stop, sheet-depressing springs connected to said front stop to facilitate the secondary advance movement of the sheet, a 110 longitudinally-movable bar disposed transversely over said tapes, brackets connected to said bar at opposite sides of the folding-rolls, vertical guides on said brackets, slides on said guides, arms pivoted vertically on 115 said guides to swing toward and from the folding-rolls, stops limiting the movements of said arms from the folding-rolls, registering points attached to the free ends of said arms to engage slits or perforations in the paper, sheet-depressing springs connected to the 120 aforesaid slides, a longitudinally-movable rock-shaft disposed parallel with the aforesaid bar, arms extending from said rock-shaft, pitmen connecting said arms to the slides, 125 means for transmitting reciprocating motion from said rock-shaft to said bar, and mechanisms imparting reciprocating and oscillatory motion to the rock-shaft as set forth and shown.
